UNITED STATES PATENT OFFICE.

LOUIS HOCHSTADTER, OF CHICAGO, ILLINOIS.

DESIGN FOR A CAKE CONFECTION.

Application filed May 6, 1925. Serial No. 13,336. Term of patent 7 years.

To all whom it may concern:

Be it known that LOUIS HOCHSTADTER, a citizen of the United States, residing at Chicago, in the county of Cook and State of Illinois, has invented a new, original, and ornamental Design for Cake Confection, as shown in the accompanying drawing and described in the following specification.

The single figure is a perspective view of the cake confection showing my new design.

I claim:

The ornamental design for a cake confection as shown.

LOUIS HOCHSTADTER.
